UNITED STATES PATENT OFFICE.

ROBERT G. NICHOLAS, OF CLYDE, KANSAS.

SAFETY-POCKET.

1,102,946.

Specification of Letters Patent.

Patented July 7, 1914.

Application filed April 30, 1912. Serial No. 694,118.

To all whom it may concern:

Be it known that I, ROBERT G. NICHOLAS, a citizen of the United States, residing at Clyde, in the county of Cloud and State of 5 Kansas, have invented certain new and useful Improvements in Safety-Pockets, of which the following is a specification.

This invention relates to safety pockets, and has particular reference to a pocket 10 designed to constitute a part of a pair of overalls or other garment intended for use by workmen; and the invention aims primarily to provide a pocket in which the workman may carry his watch without liability 15 of the same being dropped or lost.

The invention further aims to so construct the pocket that a watch or the like disposed therein will be securely retained against loss, regardless of the manner in which the 20 workman wearing the garment may stoop or bend.

In the accompanying drawings: Figure 1 is a perspective view of the apron of a pair of overalls, which apron is provided 25 with a pocket constructed in accordance with the present invention; Fig. 2 is a horizontal sectional view on the line 2—2 of Fig. 1; Fig. 3 is a vertical sectional view on the line 3—3 of Fig. 1.

30 In the drawings, the apron, by which the pocket embodying the present invention is carried, is indicated by the numeral 1 and has attached to it the usual shoulder straps, 2. The pocket is cut from a cloth blank 35 which has parallel lateral edges 3 and 4 and a lower edge 5 which extends at right angles to the edges 3 and 4. One upper corner of the blank is cut away, as clearly shown in Fig. 1 of the drawings, so that the blank 40 has an upper edge portion 6 and a similar edge portion 7, which, however, extends in a line below the portion 6. These edge portions 6 and 7 are, however, parallel with respect to each other and with respect to the 45 lower edge 5 of the blank. At the cut-away corner of the pocket blank, the edge portions 6 and 7 are connected by a vertical edge portion 8 extending preferably at right angles with respect thereto. The lateral 50 edge portion 3 of the blank is secured to the apron 1 by a line of stitching 9, and the edge portion 4 is similarly secured to the apron by parallel lines of stitching 10. The portion of the blank between the two lines 55 of stitching last-mentioned forms, in con-

junction with the apron, a pencil-receiving pocket 11.

The lower edge portion of the pocket blank is secured by a line of stitching, as at 12, to the apron 1, and the edge portions 6 and 7 are secured respectively by lines of stitching 13 and 14. The edge portion 8 is preferably hemmed and is not attached to the apron 1, so that it forms one wall of the mouth of the pocket, the mouth being vertically disposed, as readily understood. A relatively short line of stitching 15 extends from the point of juncture of the edge portions 7 and 8 of the blank toward the lower edge 5 thereof, and the blank is stitched to 70 the apron 1 along a curved line, as at 16, and thence along a vertical line, as at 17. The line of stitching 16 extends from the inner one of the lines of stitching 10, at a point substantially opposite the point of 75 juncture of the edge portions 7 and 8, to a point above the lower edge of the blank and approximately in a vertical line with the edge portion 8, the line of stitching 17 extending vertically from this last-mentioned 80 point to the line of stitching 12. From the foregoing, it will be readily understood that the line of stitching 15 serves to restrict the pocket at a point between the point of juncture of the edge portions 7 and 8 with each 85 other and the point of juncture of the lines of stitching 16 and 17. It will further be understood that a watch inserted into the pocket will follow the curved line of stitching 16 and become lodged between the line 90 of stitching 17 and the line of stitching 9 which secures the edge portion 3 to the apron 1. Should the apron be nearly inverted, the watch or other article in the pocket thereof would lodge in the recess between the lines of stitching 9, 14 and 15 and be retained, and it will also lodge in this recess should the workman bend to the right. Should he bend to the left, the watch would 95 follow the line of stitching 16 and would lodge between this line and the line of stitching 6, but as the mouth of the pocket would then be horizontal, the watch would not be allowed to fall therefrom.

From the foregoing, it will be seen that 105 there is provided a safety pocket which may be embodied in the construction of any garment, but is especially well adapted for embodiment in overalls or other garments designed primarily for wear by workmen; 110

and it will be seen that regardless of the direction in which the workman wearing the garment, bends, the watch or other article contained in the pocket will lodge in a recess from which it can not become accidentally displaced.

What I claim is:—

A pocket having a laterally presented vertically disposed opening at its upper end and a lateral extension below said opening, the walls of the pocket being stitched together on a line extending downwardly from the upper inner corner of the lateral extension toward the opposite wall of the pocket, the walls being further stitched together on a line extending downward from the upper end of the pocket and approxi-

mately parallel to but spaced from said opening, the stitching at a point approximately in line with the lower end of said opening then extending downward and toward the lateral extension to a point spaced from but substantially in line beneath the lower end of the first line of stitching, said second line of stitching then extending downward to the bottom of the pocket approximately parallel with the side wall of said lateral extension.

In testimony whereof I affix my signature in presence of two witnesses.

ROBERT G. NICHOLAS. [L. s.]
